ATTORNEYS

UNITED STATES PATENT OFFICE.

HENRY W. SCHWALB, OF NEW YORK, N. Y.

DESIGN FOR A QUILL-HOLDER FOR LADIES' HATS.

40,404.

Specification for Design.

Patented Dec. 14, 1909.

Application filed October 21, 1909. Serial No. 523,932. Term of patent 3½ years.

To all whom it may concern:

Be it known that I, HENRY W. SCHWALB, a citizen of the United States, residing in the city of New York, borough of Manhattan, in the county and State of New York, have invented a new, original, and ornamental Design for a Quill-Holder for Ladies' Hats, of which the following is a specification, reference being had to the accompanying drawings, forming part thereof.

Figure 1 is a perspective view of a quill holder for ladies' hats, showing my design; and Fig. 2 is an end view of the same.

I claim:

The ornamental design for a quill holder for ladies' hats as shown.

HENRY W. SCHWALB.
